Mathew Andis, Racine, Wis., assignor to Adis Clipper Co., Racine, Wis., a corporation of Wisconsin

Original design application May 10, 1966, Ser. No. 2,244, now Patent No. 207,098, dated Mar. 7, 1967. Divided and this application Nov. 17, 1966, Ser. No. 4,711

Term of patent 14 years

(Cl. D9—2)

FIG. 1 is a front perspective view of a vacuum cleaner attachment for a hair clipper, showing my new design;

FIG. 2 is an enlarged elevational view thereof;

FIG. 3 is a top plan view thereof.

FIG. 4 is a rear end elevational view thereof.

FIG. 5 is a front end elevational view thereof.

FIG. 6 is a view thereof taken in cross-section on line 6—6 of FIG. 3.

The broken line showing of the hair clipper in FIG. 1 is for illustrative purposes only.

This application is a division of my copending application Ser. No. D. 2,244, filed May 10, 1966, and now Patent D. 207,098.

I claim:

The ornamental design for a vacuum cleaner attachment for a hair clipper, as shown and described.
